BOWLING BALL

Charles F. Chicarelli, Elizabeth, N. J.

Application February 2, 1940, Serial No. 316,907

7 Claims. (Cl. 273—63)

This invention relates to bowling balls and more particularly to an improved arrangement of the openings which provide gripping surfaces to better enable the bowler to impart an effective spin to the ball, thereby producing a desired "curve" or "hook" to the ball as the ball nears the pins.

Most bowlers find it desirable to impart a "curve" or "hook" to the ball causing the ball to strike at an angle between the head pin and the next adjacent right or left pin, depending on whether the bowler is right or left handed. To impart a curve to a ball, it has been customary heretofore to "grip" or "cup" the ball so as to place the center of gravity of the ball between the hand and the body of the bowler. In "cupping" the ball, it is necessary to cant or bend the wrist, and this, of course, imposes a considerable strain upon the wrist of the bowler. The bowler, however, upon releasing the ball from this grip is able, by giving his wrist a quick twist, to impart a spin to the ball. The strain of cupping the ball, together with the twisting movement of the wrist, however, results in a soreness at the wrist which, while particularly annoying to most bowlers, also impedes their control over the ball.

While bowling balls have been proposed heretofore with the thought of enabling the bowler to effect the desired curve without the accompanying soreness to the wrist, none has effectively accomplished this result. With the two-hole ball the strength of the thumb and finger gripping the ball must be devoted largely to supporting the weight of the ball so that only a very small spin can be effected by "cupping" without the danger of losing control over the ball. In the case of three-hole balls heretofore provided, the holes are so arranged in relative location and at such angles as to add but little advantage, if any, over the two-hole balls for those bowlers who desire to effect a spin to the ball. The third hole of the three-hole balls has been added, in most instances, to provide an additional means for supporting the ball with the center of gravity of the ball toward the body of the bowler. Other three-hole balls have been arranged with holes at various angles with the allegation that the same provides for a relaxed grip in delivering the ball. But none of the three-hole balls heretofore provided enables the bowler to effect any appreciable spin to the ball without experiencing a corresponding loss in control over the ball.

Bearing in mind the advantage of providing a curve ball and the disadvantages of balls here-

tofore provided, it is an object of the present invention to provide a bowling ball having holes therein arranged to better enable the bowler to impart a more effective spin to the ball than previously possible.

Another object of the invention is to provide a bowling ball having holes therein arranged to enable the bowler to more easily impart a desired curve to the ball with a greater degree of accuracy.

A further object of the invention is to provide a bowling ball which will enable bowlers to deliver a curve ball without the necessity of unduly canting or bending the wrist.

15 The above and other objects of the invention are obtained by providing the bowling ball with the thumb hole and a pair of finger holes in such an arrangement that the axis of the thumb hole lies substantially in a diametral plane with the axes of the finger holes lying on opposite sides of the diametral plane with at least one of the axes of the finger holes disposed substantially parallel to the diametral plane, and the surface openings of the finger holes being spaced at different distances from the surface opening of the thumb hole. This relative location of the several holes enables the bowler to grip the ball with the thumb and middle finger, while the ring finger is free to engage the third hole for the purpose of imparting an effective turning or spinning movement on the ball as the ball is released.

Where the thumb and middle finger need not be concerned with the effort to impart a spinning movement on the ball, the bowler is enabled 35 to better control the delivery of the ball while effecting the desired spinning movement by exerting force by means of the ring finger substantially independent and relative to the thumb and middle finger. The third hole which is adapted 40 to receive and engage the ring finger is spaced forward of the hole engaged by the middle finger, thus enabling the bowler to effect a relative movement of the ring finger with respect to the middle finger as the ball is released, thereby greatly 45 increasing the spinning movement of the ball as compared with the use of the three-hole balls heretofore provided. A rapid spinning movement being possible with the ball of the present invention, an effective part of the spinning movement 50 may be transmitted to the pins thereby engaged, causing the pins to also spin and knock down additional pins. In other words, the ball of the present invention enables the bowler to give a more effective spin to the ball with greater ease of control.

The above and other objects and advantages of the invention will become further apparent upon consideration of the following description when taken in connection with the accompanying drawing in which:

Fig. 1 is a plan view of a bowling ball having thumb and finger holes arranged in accordance with the present invention;

Fig. 2 is a partial sectional view of the ball along the line 2-2 of Figure 1; and

Fig. 3 is a fragmentary plan view of a ball showing a variation in the relative location of the finger holes.

Referring to Figs. 1 and 2 of the drawing, a bowling ball 10 is shown provided with a thumb hole 12 and a finger hole 14 whereby the ball is adapted to be gripped by the thumb and middle finger of the right hand. Beyond the hole 14 is a third hole 16 adapted to be engaged by the ring finger for the purpose of steadyng the ball and imparting a rapid spinning movement to the ball as the ball is released from the thumb and middle finger.

In order to arrange the thumb and finger holes in a relation which provides the desired grip, the axes of the thumb and middle finger holes should lie in planes substantially parallel to each other with the ring finger hole spaced beyond and a little to one side of the middle finger hole. I obtain this relation by drilling the thumb hole 12 with the axis 13 thereof in a diametral plane A—A substantially in the direction of the center 20 of the ball. The middle finger hole 14 is drilled slightly to one side of the diametral plane with the axis 15 thereof in a plane substantially parallel to the diametral plane. The direction of the axis 15 may extend in the general direction of a diametral line B—B disposed at 90° to the diametral plane A—A. The distance between the surface openings of the holes 12 and 14, as well as the angle between the axes 13 and 15 thereof, may, however, be varied to accommodate different sized hands. For example, were planes passed through the axes of the holes 12 and 14 transversely of the diametral plane A—A, the angle therebetween might be varied between 58° and 84° and still provide a comfortably relaxed grip for the hand.

The third hole 16 is preferably located beyond the hole 14 with a surface thereof in tangential relation with the diametral plane A—A. While the hole 16 is preferably slightly spaced beyond a line C—C drawn tangentially to the forward edge of the hole 14 and transversely of the diametral plane A—A, the hole 16 may also be located in tangential relation to the line C—C as shown in Figure 3, if desired.

While the hole 14 is shown to be partly intersected by the diametral plane A—A in Fig. 1, it is to be understood that under certain circumstances the hole 14 may be drilled so that the plane A—A will be substantially tangent to the surface thereof. In Fig. 3 the plane A—A is shown as being tangent to the opposed lateral surfaces of the openings 14a and 16a. The spacing between the finger holes in the direction of the plane A—A may also be varied as indicated in Fig. 3. It should, therefore, be understood that the relative positioning of the finger holes with respect to directions transverse and parallel to the plane A—A may be considerably varied as suggested in Figs. 1 and 3 to suit the hands of different bowlers.

The hole 16 is preferably drilled so that the axis 17 thereof diverges with respect to the axes

18 of the hole 14, as indicated in Fig. 2. The reason for this divergence will be apparent when one holds the thumb and middle finger for insertion in the holes 12 and 14. The ring finger 5 will extend outwardly and beyond the middle finger at a diverging angle to the middle finger. This positioning of the fingers being natural will provide a comfortable relaxed grip on the ball so that accurate delivery with the desired curve is 10 feasible. With the holes thus arranged, the ring finger is capable of steadyng the ball while the ball is swung by the bowler preparatory to delivery, and upon release from the thumb and middle finger, the ring finger may be drawn inwardly of the hand so as to effect a rapid counterclockwise spinning movement to the ball. The usual upward and lateral swinging movement of the hand and arm may also be employed to assist this finger movement.

20 The spinning movement which is greatly enhanced by the positioning of the hole 16 with respect to the hole 14 may be added to the "cupping" effect to impart even a greater spin to the ball. Thus, bowlers accustomed to cupping the ball will find they are able by the arrangement 25 of the holes in the ball of the present invention to increase the spinning effect. The bowler, if he so desires, may cup the ball with less bending of the wrist and at the same time give the ball 30 a more effective spinning movement than possible with balls heretofore provided.

In the case of left handed bowlers, the location of the finger holes will, of course, be reversed with respect to the diametral plane A—A.

35 It will be apparent from the foregoing description that many variations are possible in the present invention, such as variations in the relative positioning of the holes 14 and 16 with respect to the diametral plane A—A and the line C—C without departing from the spirit of the invention. For this reason, it should be understood that the forms of the invention herein illustrated and described are intended to be illustrative of the invention only and not as limiting 40 the scope thereof.

45 I claim:

1. A bowling ball having a substantially cylindrical thumb hole and a pair of substantially cylindrical finger holes therein, the axis of the thumb hole lying substantially in a diametral plane, the axes of said pair of finger holes being on opposite sides of the diametral plane with at 50 least one of the axes of said finger holes lying in a plane substantially parallel to said diametral plane and the surface openings of said finger holes being spaced apart along said diametral plane so that the ring finger of a bowler will be in a position forward of the middle finger.

2. A bowling ball having a substantially cylindrical thumb hole and a pair of substantially cylindrical finger holes therein, the axis of the thumb hole lying substantially in a diametral plane, and the surface openings of said finger holes being spaced apart along said diametral plane with the intermediate finger hole partly intersected by said diametral plane and the forwardmost finger hole located in substantial tangential relation with said diametral plane.

3. A bowling ball having a substantially cylindrical thumb hole and a pair of substantially cylindrical finger holes therein, the axis of the thumb hole lying substantially in a diametral plane with the axis of at least one of said finger holes lying in a plane substantially parallel to said diametral plane, one of the finger holes

being at least in part intersected by said diametral plane, and the other of said finger holes being in substantial tangential relation with said diametral plane.

4. A bowling ball having a substantially cylindrical thumb hole and a pair of substantially cylindrical finger holes therein, and the surface openings of all three holes being so disposed that they are interceptable by the same great circle.

5. A bowling ball having a substantially cylindrical thumb hole and a pair of substantially cylindrical finger holes therein, the axis of the thumb hole lying substantially in a diametral plane, and the surface openings of said pair of holes being spaced apart along and tangent to said diametral plane.

6. A bowling ball having a substantially cylindrical thumb hole and a pair of substantially cylindrical finger holes therein, the axis of the thumb hole lying substantially in a diametral plane, and the axes of said pair of finger holes being on opposite sides of the diametral plane with the surface openings of said pair of holes spaced apart along said diametral plane, the axes

of the thumb hole and the intermediate finger hole being in an inward direction converging toward each other, while the axis of the forward-most hole is in an inward direction diverging from the axis of the intermediate finger hole, the divergency being parallel to the diametral plane.

7. A bowling ball having a substantially cylindrical thumb hole and a pair of substantially cylindrical finger holes for the middle and ring fingers respectively, the axis of the thumb hole lying substantially in a diametral plane, and the axes of said pair of finger holes being on opposite sides of the diametral plane, and the surface openings of said ring finger and middle finger holes being spaced apart and in overlapping relation in a direction along said diametral plane so that the ring finger is adapted to extend considerably beyond the middle finger during gripping of the ball, thereby enabling the ring finger to be moved through a substantially larger arc than the middle finger to exert a definite spinning torque or movement to the ball upon release thereof.
